UNITED STATES PATENT OFFICE.

ADAM J. MAY, OF ROCHESTER, NEW YORK, ASSIGNOR, BY MESNE ASSIGNMENTS, TO RITTER DENTAL MFG. CO., OF ROCHESTER, NEW YORK, A CORPORATION OF DELAWARE.

DENTAL CHAIR.

Application filed November 20, 1923. Serial No. 675,963.

This invention relates to adjustable supports of the variety adapted for use for example, with dental, surgical, barbers' and other chairs, for supporting and adjusting the same to different elevations, one object of the invention being to provide improved apparatus of this character having a simple, compact and efficient form of construction capable of being operated by a self-contained 10 electric or other motor of small size and power. Another object is to provide a motor actuated device of this variety having an advantageous form of control means including devices operating automatically to stop the 15 movement of the parts when the latter reach the limits of their range of adjustment. A further object is to provide such an apparatus so constructed that the relatively movable, weight sustaining parts engage each other by 20 means of rolling bearing members to substantially eliminate friction therebetween and reduce the power required for operation. Still a further object is to provide a mechanism of this type having a driving connection 25 with its motor of such a character as to lock the parts against operation except when driven by the motor.

To these and other ends the invention resides in certain improvements and combinations of parts all as will be hereinafter more fully described, the novel features being pointed out in the claims at the end of the specification.

In the drawings:

Fig. 1 is a central sectional elevation of apparatus embodying the present invention;

Fig. 2 is a detail sectional view on the line 2^a—2^a in Fig. 1;

Fig. 3 is a sectional elevation in a plane at 40 right angles to Fig. 1 or on the line 3^a—3^a in Fig. 9, and showing the parts in a different position;

Fig. 4 is an enlarged sectional detail of an actuating nut and spindle means;

Fig. 5 is a plan view of the same;

Fig. 6 is an enlarged central sectional elevation of actuating parts shown in Fig. 1;

Fig. 7 is a sectional detail on the line 7^a—7^a in Fig. 6;

Fig. 8 is an elevation of a control means;

Fig. 9 is a plan view partly broken away and partly in section on the line 9^a—9^a in Fig. 1, and

Fig. 10 is a similar view partly in section on the line 10^a—10^a in Fig. 1.

Similar reference numerals throughout the several views indicate the same parts.

The embodiment of the invention disclosed herein, by way of illustration of the principles involved, comprises, preferably, a base portion, indicated generally at 20, Figs. 1 and 3 on which are carried vertically adjustable parts the uppermost of which provides a support 21 for the chair body proper. The base has a substantially horizontal bottom flange 22 of ample diameter adapted to rest on and be secured to the floor. Formed integrally with this flange is an upwardly extending cylindrical portion or sleeve 23 in the upper half of which are circumferentially spaced pairs of bearing rollers 24, with the rollers of each pair arranged one above the other, each roller being rotatably supported by trunnions journaled in suitable brackets on the sleeve as shown. These rollers serve to guide the vertical movement within the sleeve 23 of an intermediate sleeve 25 of the generally oval transverse shape shown in Fig. 9 and formed externally at the center of its longer sides with tracks 26 for the rollers 24 so disposed that the latter serve also to prevent rotation of the intermediate sleeve. The latter is preferably though not necessarily of substantially the same length as sleeve 23 of the base within which it telescopes and carries within it peripherally spaced pairs of rollers 27 arranged and rotatably supported substantially as described above in connection with the base sleeve 23. Rollers 27 engage tracks 28 on a substantially cylindrical sleeve 29 depending from the chair support 21 and guide the latter for vertical adjustment telescopically within the intermediate sleeve 25, while holding it against rotation. The support sleeve 29 is preferably about equal in length to sleeves 23 and 25. The upper end of sleeve 29 rotatably engages a depending flange 30 fixed to support 21 to which however sleeve 29 is normally clamped by any known or suitable means such for ex-

- ample as the lever operated device indicated generally at 31 which latter however, forms no part of the present invention and therefore requires no further description except 5 to point out that by means of it the support may be unclamped from sleeve 29 for rotating the chair to a desired position, after which the parts are again clamped together before elevational adjustment is made.
- 10 It is apparent from the above description that the support 21 and its depending sleeve 29 are guided for elevational movement within the intermediate sleeve 25 and the latter in turn within the base sleeve 23 and means 15 are provided for effecting such movements, which will now be described.
- The base has a bottom plate 32 secured thereto as by means of dowels 33 and screws 34 and formed centrally with a bearing recess 35 in which is rotatably mounted at its lower end a vertically extending screw threaded spindle 36. The latter carries at its lower end a gear 37 forming part of a drive transmitting connection with an electric motor presently to be described, for rotating the spindle in either direction to raise and lower the support respectively. Spindle 36 extends through a cooperating internally threaded part 38, in the present instance in 20 the form of a nut fixed as by means of set screws 39 in a seat in a ring 40 fixed by screws 41 concentrically in the lower end of sleeve 25, the threads of the nut being connected with those of the spindle by a plurality of rolling bearing members for eliminating friction as hereafter described. It is apparent therefore that rotation of spindle 36 in one direction or the other serves to raise or lower the intermediate sleeve.
- 25 The means for effecting elevational movement of the support relative to the intermediate sleeve comprises, preferably, an inner sleeve 42 surrounding spindle 36 and provided at its lower end with a thrust bearing 43, of the ball and race variety, on the upper end of nut 38, Figs. 1 and 6, the sleeve being thus rotatably carried by the intermediate sleeve 25 and moving vertically with the latter. Inner sleeve 42 is rotated by a sliding form of 30 connection with spindle 36 comprising rollers 44 rotatably carried in heads 45 set into dovetailed slots in the upper end of the spindle as shown also in Figs. 6 and 7. These rollers travel in vertical slots 46 formed in the inner sleeve 42 and the latter is thus rotated by the spindle, while freely adjustable vertically with the intermediate sleeve 25 by which it is carried.
- 35 The rotatable inner sleeve 42 has an actuating connection with support 21 comprising in the present instance a threaded part 47 preferably in the form of a nut fixed as by means of dowel pins 48 to the top of a cap 49 secured on the upper end of sleeve 42 40 which thus rotates the nut 47 whenever spin-

dle 36 is rotated. Nut 47 cooperates with a threaded spindle 50 depending concentrically from support 21, this pair of threaded parts being also connected by rolling bearing members as hereafter more particularly 70 described. Spindle 50 has its upper end fixed as by means of a bolt 51 to the support so that the latter, which is held against rotation as already described, is raised or lowered as nut 47 is rotated in one direction or the other 75 by the rotation of spindle 36. It is noted that the support not only acquires the elevational movement imparted to intermediate sleeve 25 through the cooperation of spindle 36 and nut 38 but also the additional elevational movement relative to the intermediate sleeve imparted by the cooperation with the support spindle 50 of the nut 47 which is rotated by spindle 36. In other words the intermediate sleeve and support have a differential elevational movement relative to the base so that the support is afforded a movement of substantial range and velocity by parts which furthermore telescope compactly one within another.

80 The construction of the spindle and nut means for eliminating friction therebetween is best shown in Figs. 4, 5 and 6, from which it may be seen that the adjacent threads have intervals therebetween of substantially semi-circular profile adapted to receive a plurality of rolling bearing members in the form, in this instance, of balls 52, each of which rolls in engagement with both the spindle and nut so that the latter have, substantially a frictionless rolling bearing on each other. The balls fill the threaded intervals within the nut and a continuous channel 53 is formed in the nut with its ends connected with the respective 85 ends of the thread of the latter for receiving the balls as they roll out of the nut thread at one end and for supplying the same to the nut thread at its opposite end. The end of the nut thread is provided with a finger 54 for preventing the balls from escaping from 90 the nut and for directing the same into the channel so that the balls are retained within the nut and constantly supplied to the thread of the latter as it moves up and down the spindle. Substantially the same construction 95 is employed in the second or upper nut 47 and the various weight supporting parts of the apparatus thus engage one another through rolling bearing members, with the result that frictional resistance is substantially eliminated 100 and the various parts move smoothly and quietly upon each other and with a minimum 105 of wear.

110 The means for rotating the spindle 36 comprises the gear 37 fixed on the lower end of the latter and having a thrust bearing on the base plate 32, of the ball and race variety, 35, shown in Fig. 6. Meshing with gear 37 is a gear 56 115 rotatably supported on the base plate and meshing in turn with a gear 57 also rotatably 120 125 130

supported on the plate and fixed on the lower end of an upright shaft 58 journaled at its upper end in a frame member 59. Fixed on the upper end of the shaft is a worm wheel 60 driven by a worm 61 on the shaft 62 of a driving motor 63 supported on an extension 64 of the flange. Motor 63 is preferably of the series wound reversible type for either raising or lowering the support and it is to be noted that its connection with the adjustable parts comprises the worm and worm wheel described above which serve as an automatic lock for holding the parts against movement except when actuated by the motor.

15 The latter is controlled by a combined pedal and automatic device illustrated in Figs. 8 and 10 and comprising an operating controller 65 mounted in a recessed portion 66 conveniently located in the vertical wall of the base adjacent its bottom. The controller has a stationary supporting plate 67 provided with a plurality of concentric arcuate contacts 68 to 72 inclusive fixed on the plate and insulated from each other. The plate rotatably supports at 25 its center a spindle 74 having fixed thereon a hub carrying oppositely extending arms 75 and 76, each of which is provided on its under side with conducting strips 77 as shown for connecting radially spaced, adjacent pairs of 30 the contacts 68 to 72. Fixed to the hub also are oppositely extending pedals 78 and 79 and a leaf spring 80, supported at its center in any suitable manner, has its ends engaged with the pedals respectively for returning the latter 35 to the neutral position shown in Fig. 8. Pedals 78 and 79 are moved by the operator for either elevating or lowering the chair as more fully explained hereafter.

Supported on the inner surface of the wall 40 of the base is a bar 81 on which are mounted a pair of switch means 82 and 83. Each of these comprises an arm 84 pivotally supported at 45 85 on bar 81 and carrying a contact piece 86 for engagement with one or the other of a pair of fixed contact points 87 and 88, the switch arm being stopped in position over one or the other of these contact points by stop pins 89. The switch arms are engaged and swung by a finger or pin 90 projecting from 50 the elevating sleeve 25, the switches being located adjacent the desired limits of movement of the finger so that the latter raises the arm of the upper switch and depresses the arm of the lower switch as the elevating parts reach 55 their upper and lower limits of movement, respectively. Springs 91 normally retain the switch arms in their opposite positions. The contact points 87 of each switch are connected by a conductor as shown with contact 69 of the 60 controller and the other contact of each switch is connected with the contact 70. Contact 68 is connected by a conductor 92 with the field of the series wound motor, the other terminal of which is connected with one side of the power line. Contact 71 is connected by a conductor

93 with one armature terminal of the motor while contact 72 is connected by a conductor 94 with the other armature terminal. The other side of the line is connected to each of the switch arm contact pieces 86.

70 It is evident from the above described devices and circuits that when the pedals 78-79 are in the neutral position shown, the motor circuit is open and the apparatus is stationary. When the chair elevating parts occupy 75 an intermediate position, movement of the controller pedals in one direction connects the motor with the line in such a manner that the chair support is elevated as long as the controller pedals are held in such position 80 or until the upper switch arm 84 is thrown by the means described to its uppermost position which breaks the circuit and stops the motor. In this extreme position the motor circuit can only be closed by moving the controller pedals in the opposite direction for 85 starting the support downwardly, in which latter position the motor circuit, of course, is connected with the line in a reverse sense. If the chair supporting parts are moved by 90 the controller to their extreme lower position, the lower switch is operated in a similar manner to break the circuit so that the motor can then be connected with the line only in such a sense as to raise the chair.

95 The invention thus comprises a relatively simple and effective pedal control means by which the motor may be quickly started in either direction for raising or lowering the parts and quickly stopped in a desired position of the latter, a brake means of known variety being provided for the motor, if desired for stopping it more rapidly. In any stationary position of the parts they are securely retained against movement by the worm and worm wheel driving connection with the motor until the latter is again actuated. When the elevating parts reach either limit of movement they are stopped by the automatic limit switch means described 100 105 which dispose the circuits in such a way that the pedal controller is then effective only for moving the parts in the opposite direction.

110 The operation of the apparatus has been 115 fully disclosed in connection with the above description of its construction and it is evident that the latter is simple and practical in character comprising comparatively few parts so designed and arranged and connected by rolling bearing members as to reduce frictional resistance to a minimum. The apparatus is thus capable of being efficiently operated by an electric motor of small size and power consumption. The parts are furthermore of a strong and durable nature having a pleasing simplicity of appearance. The apparatus is furthermore controlled by a convenient and fool proof device by means of which the support for the chair or other part 120 125 130

may be quickly, smoothly and quietly raised or lowered to any desired position within an ample range of movement.

I claim as my invention:

- 5 1. In apparatus of the character described, the combination of a base, a support guided for elevational movement on said base, cooperating parts comprising a screw and a nut on said base and support each provided 10 with a helical ball race, a plurality of ball members between said cooperating parts each rolling in engagement with said races and forming the sole connection therebetween to provide a substantially frictionless bearing, one of said parts having a vertical by-pass permitting the balls to drop by gravity to the bottom of the race, a detachable finger at the top of the nut adapted to deflect the balls into said by-pass, and means for actuating said parts to raise and lower said support.
- 15 2. In apparatus of the character described, the combination of a base, a support guided for elevational movement on said base, cooperating spindle and nut means on said base and support for elevating the latter on said base and each provided with a helical ball race, and a plurality of ball members each engaging said races and forming the sole connection between said spindle and nut to provide a substantially frictionless bearing therebetween, said nut having a vertically disposed passage leading from the top of the race whereby the balls are adapted to drop 20 by gravity to the bottom of the race and a detachable finger at the top of the nut adapted to direct the balls into said passage.
- 25 3. In apparatus of the character described, the combination of a base, a supporting portion guided for elevational movement relative to said base, a spindle rotatable on said base and provided with a helical ball race, a nut carried by said portion for cooperation with said spindle and also provided with a helical ball race, a plurality of ball members each engaging said races and forming the sole connection between the said spindle and nut to provide a substantially frictionless connection therebetween, said nut having a 30 vertical passage permitting the balls to drop by gravity from the top to the bottom of the race, a detachable finger at the top of the nut for deflecting the balls into said passage and means for rotating said spindle to elevate said supporting portion.
- 35 4. In apparatus of the character described, the combination of a base having a rotatable threaded part, a portion provided with means guiding the same for elevational movement without rotation on said base, a threaded part on said portion cooperating with said threaded base part, a sleeve rotatably carried by said portion about said threaded base part, a sliding connection between said threaded base part and sleeve for rotating the latter, a

threaded part fixed to said sleeve, a support and a threaded part fixed to said support and cooperating with said threaded sleeve part.

5. In apparatus of the character described, the combination of a base having an external- 70 ly threaded, hollow, rotatable spindle, a portion provided with means guiding the same for elevational movement without rotation on said base, a threaded part on said portion 75 cooperating with said spindle, a sleeve 75 rotatably carried by said portion about said spindle, a connection between said spindle and sleeve adjustable longitudinally thereof for rotating the sleeve, a threaded part fixed to said sleeve, a support a threaded spindle 80 fixed to said support for cooperation with said sleeve part and positioned for reception in said hollow base spindle; a plurality of ball bearing members connecting the threads of each of said spindles with its correspond- 85 ing threaded part, and means for rotating said base spindle.

6. In a device of the character described, the combination of a base having an upwardly extending sleeve, an intermediate sleeve 90 slidable longitudinally in said base sleeve and having a threaded part fixed thereon, a support having a sleeve slidable longitudinally in said intermediate sleeve, means guiding said intermediate and support sleeves and 95 preventing rotation thereof, an inner sleeve rotatably carried by said intermediate sleeve and having a threaded part fixed thereon, a threaded spindle fixed to said support for cooperation with said inner sleeve part, a 100 threaded spindle rotatable on said base for cooperation with said intermediate sleeve part and engaging said inner sleeve to rotate the same, and ball bearing members connecting the threads of each spindle with those 105 of the cooperating threaded part.

7. In apparatus of the class described, the combination of a base, a sleeve reciprocally mounted within the base, a nut fixed upon the sleeve, an upstanding screw rotatably supported by the base and threaded into said nut, an inner sleeve disposed within the first mentioned sleeve and rotatably supported by said nut and adapted to be rotated by said screw, a second nut connected with the upper 115 end of the inner sleeve and adapted to be rotated thereby, a screw threaded through said second nut and projecting downwardly into the inner sleeve, a support carried by the second mentioned screw and including a portion projecting between and guided by one of the sleeves and means for rotating the first mentioned screw.

8. In apparatus of the character described, the combination of a base, a rotatable screw 125 threaded member mounted thereon, a second screw threaded member cooperating with said first-named member and movable axially with respect thereto when said first and second screw threaded members are rotated 130

relative to each other, a support, a third screw threaded member mounted on said support, a fourth screw threaded member cooperating with said third screw threaded member and 5 movable axially with respect thereto when said third and fourth members are rotated relative to each other, said fourth screw threaded member being rotatably mounted on said second threaded member, and means including an anti-friction roller and a surface 10 cooperating therewith for operatively connecting said first threaded member to said fourth threaded member to transmit the rotations of the former to the latter while allowing relative axial movement thereof.

ADAM J. MAY.
